UNITED STATES PATENT OFFICE.

HENRY MENKE, OF PHILADELPHIA, PENNSYLVANIA.

DESIGN FOR A MONEY-JUG.

SPECIFICATION forming part of Design No. 21,231, dated December 8, 1891.

Application filed June 10, 1891. Serial No. 395,814. Term of patent 7 years.

To all whom it may concern:

Be it known that I, HENRY MENKE, a citizen of the United States, residing in the city of Philadelphia, State of Pennsylvania, have

5 invented and produced a certain new, useful, and original Design for a Money-Jug, of which the following is a full, clear, and exact description, reference being had to the accompanying drawings, forming a part of this specification.

10 My invention has relation both to the external form or configuration and to the surface ornamentation of an article of manufacture known as a "money-jug;" and it consists, first, in the form or shape of the article, as 15 shown in the drawing, which most nearly resembles that of an egg with a flattened bot-

tom, the slot being near the top, and in the ornamentation thereof by peripheral bands, forming a central peripheral space thus divided off. 20

Having thus described my invention, what I claim is—

The design for the external configuration and ornamentation of an article of manufacture known as a "money-jug," substantially as 25 shown and set forth.

In testimony whereof I have hereunto affixed my signature this 28th day of May, A.D. 1891.

HENRY MENKE.
